UNITED STATES PATENT OFFICE.

EVAN H. WADE AND JOHN L. NICHOLSON, OF CHICAGO, ILLINOIS,
ASSIGNORS TO AMERICAN LOCOMOTIVE EQUIPMENT CO., OF
CHICAGO, ILLINOIS, A CORPORATION OF ILLINOIS.

LOCOMOTIVE-BOILER FURNACE.

No. 820,450.

Specification of Letters Patent.

Patented May 15, 1906.

Application filed September 13, 1904. Serial No. 224,305.

To all whom it may concern:

Be it known that we, EVAN H. WADE and JOHN L. NICHOLSON, citizens of the United States, residing in Chicago, in the county of Cook and State of Illinois, have invented a certain new, useful, and Improved Locomotive-Boiler Furnace, of which the following is a specification.

Our invention relates to locomotive-boilers and to improvements in the furnaces thereof.

The invention has further and special reference to improvements upon the furnace which is shown and described in Letters Patent No. 744,135, granted to E. H. Wade, J.

15 L. Nicholson, and S. C. Smith, November 17, 1903.

The object of our invention is to improve combustion in locomotive-boiler furnaces and in furnaces generally, and the particular object of our invention is to improve the construction and operation of the aforesaid patented furnace and add to the effectiveness thereof.

It is well known that locomotive-boiler furnaces are deficient in grate area and that to secure the requisite evaporation of water it is necessary to force their fires. This is done by a blast of steam created from the exhaust of the engines, and said blast is so powerful that the draft through the furnace-grate is sufficient to disrupt the fire and uncover parts of the grate unless much care is exercised in firing the furnace. It is also well known that the combustion in locomotive-boilers is very imperfect and that in efficiency locomotive-furnaces compare unfavorably with stationary-boiler furnaces.

Combustion proceeds upon a fixed principle. The inefficiency of locomotive-boiler furnaces is due to their peculiar form and disproportionate size, resulting in an inadequate supply and admixture of air to and with the combustible products. Our purpose is to take advantage of the partial vacuum that is created in the fire-box of a locomotive-boiler and cause or admit an inrush of air above the grate to reduce such vacuum, and thereby prevent the disruption of the fire and also supplement the volume of air normally drawn through the grate. In brief, a distinct object of our invention is to provide a furnace that shall combine the

principles and effects of both updraft and downdraft furnaces. The completeness to which combustion will progress in fuel is dependent upon the intimacy of admixture between the combustible products and oxygen from the atmosphere and upon whether or no oxygen is supplied in sufficient quantities to make proper combinations with all said products. We provide means to form within the furnaces a restricted throat or opening between the fire and combustion chambers and to maintain thereacross a barrier of air which all the fuel elements and gases from the fire-chamber must penetrate in order to reach the combustion-chamber of the furnace, and, further, by the same means we provide for an adequate and sufficient supply of air not only to the bottom of the fire upon the grate, but also to the upper surface of the body of the burning fuel, to insure intimate and complete combination of the rising gases with the admitted air.

Specifically defined and as herein shown, our invention consists in a boiler-furnace comprising a fire-box having a grate and divided into fire and combustion chambers by transverse arches between which is an opening or throat leading from the fire-chamber into the combustion-chamber. The ends of the walls or arches which outline or define the throat of the furnace we provide with air-entrance openings or cavities and with deflectors or deflecting-surfaces that tend to cause the moving of air there admitted to descend upon the fire on the grate. The construction is such that the two or more currents of air entering through said walls or arches together constitute a complete air barrier beneath and across the furnace-throat, through and with which supplied air the fuel-gases must pass and unite before reaching the combustion-chamber. Through recognition of a true principle of admixing fuel-gases and air we have remedied the defects in earlier furnaces by so arranging the air ducts or passages of the furnace-dividing walls or arches that the currents or sheets of hot air entering therethrough will because of their lower temperature, their velocity, and fixed direction flow or fall toward and upon the burning fuel beneath and also converge at a point below the throat of the furnace, thus providing for and

maintaining a complete barrier of hot air beneath the furnace-throat and therefrom enriching the fuel-gases and elements to the extent required for their complete combustion 5 within and above said throat.

Our invention further consists in the combination of a furnace and its grate with transverse walls or arches separated by an opening or throat and which prevent the direct passage of the combustibles and products of combustion from the burning fuel to the boiler-flues and which contain air-supplying ducts and deflectors through which air is drawn into the furnace, heated, and, so to 10 speak, "poured" upon the surface of the burning fuel to prevent excessive effects of vacuum within the furnace and insure the complete combustion of the fuel products rising from the grate; and, further, our invention 15 consists in walls or arches having the above characteristics and functions and which are self-sustaining within the furnace—in other words, such as may be employed with or without the arch-tubes which are found in many locomotive-boiler furnaces; and, further, our invention consists in various details of construction and in combinations of parts, all as hereinafter described, and particularly 20 pointed out in the claims.

30 The invention will be more readily understood by reference to the accompanying drawings, forming a part of this specification, and in which—

Figure 1 is a longitudinal section of a 35 boiler-furnace embodying our invention. Fig. 2 is a view of the rear end of a boiler, the furnace and the rear arch therein being shown in dotted lines. Fig. 3 is a compound vertical section of a boiler, one half of the view being on the line A³ A³ of Fig. 1 and the other half on the line B³ B³ of Fig. 1 viewed in the direction of the arrows. Fig. 4 is a vertical section on the irregular line C⁴ C⁴ of Fig. 1 viewed in the opposite direction as shown by 40 arrows. Fig. 5 is a vertical section on the line D⁵ D⁵ of Fig. 1. Fig. 6 is a sectional view on the line E⁶ E⁶ of Fig. 1. Fig. 7 is a horizontal section on the irregular line F⁷ F⁷ of Fig. 1 viewed from beneath as indicated 45 by arrows. Fig. 8 is an end view of the throat framing or outlining bricks; and Fig. 9 is an end view of a pair of intermediate hollow or channeled bricks, several pairs of which are used in the front arch, while usually 50 only a single pair is employed in the rear arch.

55 The boiler represented in the drawings is of a common locomotive type.

2 is the shell of the boiler, which contains the furnace, whereof 3 is the flue-sheet. 60 4 is the crown-sheet, 5 the rear end, and 6 6 the side sheets or walls. The rear end contains the door-opening 7, and the bottom of the furnace is closed by the usual grate 8. The furnace proper is surrounded by the 65 usual water-legs 9, and 10 10 represent the

boiler-flues, leading to the front end of the boiler.

It is not our intention to confine our invention to walls or arches of special form or to any special manner of providing a restricted 70 throat in the furnace and supplying downwardly-directed currents or sheets or air in proximity thereto. We, however, prefer to employ front and rear arches erected in the front and back portions of the furnace and somewhat resembling the arches illustrated 75 in the aforesaid patent. Each arch contains one or more air-heating passages, which terminate in cavities or openings in the under side of the arch and near the inner end thereof. 80 These openings or cavities extend entirely across the furnace, and the air admitted therethrough is therefore evenly distributed across the furnace and by reason of the form of the inner walls of said cavities directed 85 downwardly in such manner that the air-currents from the two arches will converge or meet at a point beneath the throat of the furnace and upon or somewhat above the fuel on the grate. We prefer to make our 90 arches of refractory material formed into suitable shapes or bricks. The rear arch is usually composed of two pairs of bricks 11 11 and 12 12. The bricks are of greater width than length and together bridge the top of 95 the fire-box. They are supported upon studs 13 on the side walls of the fire-box and are arched against one another, the meeting joint 14 being strengthened by a tongue and groove 15. Each brick 11 is provided with 100 one or more air-passages 16, to which air is supplied from tubes, thimbles, or hollow stay-bolts 17, extending through the rear water-leg of the boiler. The inner pair of 105 terminal bricks 12 12 of the rear arch possess the same cross-sectional curve as the pair 11 11, but instead of having tubular passages 16 are provided with cavities or grooves 18 in their under sides. It will be noted that 110 the ends of these bricks are strengthened by ribs or webs 12'. The tops of the cavities 18 communicate with the passages 16, and the inner walls 19 of the cavities are downwardly inclined at a slight angle to the vertical to deflect the air entering through channels 16 in a downward direction upon or toward the fuel on the grate. 13' represents 115 stops or lugs on the side walls of the furnace for preventing longitudinal movement or displacement of the rear arch.

120 The front arch of the furnace is composed of a pair of end bricks 20 20, substantially identical with the bricks 12 12 of the rear arch, having the same cavities 21 and corresponding deflector surfaces or walls 22. The 125 lower bricks 23 of the front arch are identical or substantially identical with the bricks 11 11, the same having like air-passages 23', which communicate one with the other in abutting bricks. The bottom pair of bricks 130

23" are slightly different in shape, the curve thereof being finally merged into a straight line 24 and certain of the ducts 23' being restricted in size toward the lower end. The 5 thimbles or tubes 25 in the front water-leg of the boiler communicate with the passages 23', and the air under the impetus of external pressure passes upwardly therein to be discharged downwardly from the deflector-surfaces with such velocity as to converge with the streams or currents from the rear arch. The lower front face of the bottom brick of the front arch presents the appearance shown in Fig. 3, and by thus relatively depressing 10 the lower end of the arch at the middle we are able to avoid closing any of the boiler-flues and also to have the arch-passages communicate with air-tubes 25, that are directly beneath the bottom of the boiler-shell, there- 15 by providing for an equal distribution of the air transversely across the hollow arch. The bricks composing the front arch have tongue or groove joints, as in the case of the rear arch, and in like manner are supported by 20 lugs or angles 13 on the side sheets of the furnace. The bricks being composed of fire-clay are refractory and being constantly cooled by the air flowing in the channels or 25 passages are capable of withstanding the intense heat of the furnace for a long period and in this regard are preferable to the ordinary solid arch-brick. The highest temperature in the furnace is found in the top thereof above the arches, and we prefer to make the 30 top walls of the arch-passages thinner than the lower walls in order that they may be disproportionately cooled, and hence equally 35 well preserved.

The operation of our invention is as follows: 40 The exhaust-nozzle (not shown) in the front end of the locomotive-boiler causes a heavy draft of air upward through the grate, as required to maintain combustion thereon. The partial vacuum in the furnace-chamber 45 caused by the exhaust of gases through the boiler-flues results in the inflow of large volumes of air through the tubes 17 and 25 and the hollow or channeled arches wherewith they communicate. The bricks composing 50 the arches are heated to a high degree, and the air entering therethrough is perfectly prepared for admixture with the gases evolved from the fuel. Although the incoming air is intensely hot, it is nevertheless cooler than 55 the surface of the body of burning fuel and also cooler than the ascending gases. The rapidly-moving air-currents being deflected by the end bricks of the arches are directed downwardly. Furthermore, the air being 60 cooler and heavier than the rising gases falls naturally, and part thereof spreads upon the fire. Thus the intensity of combustion upon the grate is increased. The downward movement of the currents or sheets of air from the 65 two arches is resisted by the updraft through

the furnace, and said updraft tends to deflect said currents or streams of air, thus causing them to converge beneath the throat of the furnace. In this manner a complete curved stratum or, as we prefer to call it, an 70 "air barrier" is created and maintained in and across the upward path of unconsumed fuel products and poor gases. All of the combustibles are forced to pass through this barrier, and it is obvious that they are enriched 75 with oxygen therefrom, complete combustion being thereby insured. It is also obvious that the air which is admitted around and below the throat of the furnace, although already hot, will quickly attain a still higher 80 temperature because of its admixture with the fire-box products and gases, and hence the more quickly enters into combination therewith.

It is substantially true that only perfectly 85 enriched or prepared combustibles escape through the throat of the furnace and that final and complete combustion occurs in the combustion-chamber directly beneath the crown-sheet, as evidenced by the absence of 90 smoke from the stack of the locomotive. It should be noted that the rear arch overhangs the furnace-door, and the effect of said arch and of the air-currents projected downwardly therefrom is to prevent the direct 95 passage of cold air over the top of the front arch when the furnace-door is opened. Instead the blast of air entering at the door is deflected by the downwardly-moving currents or sheets of air from the rear arch and is 100 spread over the fire, and the usual sudden depression of temperature in the top of the fire-box, with consequent failure of combustion, is avoided. A distinct advantage of 105 our invention is that the reduction of vacuum in the furnace secured by the admission of air is sufficient to suppress the strong draft and prevent carrying over of cinders, and the top of the arch and the lower flues of the 110 boiler are no longer found loaded with cinders, as in the past.

It will be obvious that the throat of the furnace may take various shapes and forms and that there are many ways of introducing air and maintaining the described air barrier 115 between the furnace-throat and the burning fuel on the grate. When the flow of air through the arches is due to reduced pressure (vacuum) in the furnace-chamber, the inclined deflectors are needed to change the 120 direction of the currents and cause them to converge; but when a source of external pressure is available nozzle-like air-openings may be used around the furnace-throat and the draft induced by the exhaust-nozzle may be 125 lessened. As numerous modifications of our invention will readily suggest themselves to one skilled in the art, we do not confine the invention to the specific constructions herein shown and described.

Having thus described our invention, we claim as new and desire to secure by Letters Patent—

1. A furnace-chamber, having a suitable grate and provided with a fuel-opening and a smoke-outlet, in combination with a partition or arch extending from side to side and from end to end of said chamber, above said fuel-opening and below said smoke-outlet, 5 said partition or arch having an intermediate-located opening or throat and dividing said furnace into fire and combustion spaces or chambers, means for admitting air into said furnace-chamber from points adjacent 10 to the walls of said opening or throat and for directing the admitted air downwardly from such points and thereby maintaining a barrier of air across said throat and within said fire-chamber, through which barrier the 15 combustibles must all pass to reach said combustion-chamber, substantially as described. 20
2. A furnace-chamber having a grate, a fuel-opening and a smoke-outlet, in combination with arches arranged transversely in said 25 chamber and dividing it into fire and combustion chambers, there being a relatively small opening or throat between the adjacent ends or edges of said arches through which substantially all of the combustibles 30 from the fire-chamber must pass to reach the combustion-chambers and means for projecting streams of hot air toward the grate and thereby maintaining a barrier of hot air across said throat beneath said arches, substantially as and for the purpose specified. 35
3. A furnace-chamber having a suitable grate, and provided with a fuel-opening and a smoke-outlet, in combination with an arch or partition of refractory material, extending 40 from side to side and from end to end of said chamber and containing an intermediate opening or throat through which substantially all of the combustibles must pass, said arch being provided with downwardly-opening 45 air-passages in its under side adjacent to said throat and said passages being arranged to direct streams of air across said throat in both directions to form and maintain a complete barrier of air beneath the same for enriching the combustibles before the same pass through said throat, substantially as described. 50
4. A furnace-chamber having a grate, a fuel-opening and a smoke-outlet, in combination 55 with a refractory arch arranged between said grate and said outlet, and provided with a relatively small throat for the passage of combustibles therebetween, and means for forcibly projecting streams of hot fresh air 60 downwardly from said arch and completely across said throat to constitute and maintain an air barrier, through which all the combustibles must pass before entering said throat, substantially as described. 65
5. A furnace, having a grate, a fuel-open- 70
- ing and a smoke-outlet, in combination with an arch of refractory material arranged in said furnace and dividing the same into fire and combustion chambers, and provided with a restricted throat or passage, said arch 75 being provided with air-heating ducts and openings adapted to direct currents of air downwardly in opposite directions across said throat, in such manner as to cause said currents to converge within the fire-chamber 80 and form a complete air barrier coextensive with said throat, substantially as described. 85
6. A furnace-chamber, provided with a grate, a fuel-entrance and an outlet, in combination with arches arranged in said chamber 80 and provided with air-entrance channels, means at the inner ends of said arches for deflecting the air admitted therethrough toward said grate and transversely across and beneath the throat between the arches, substantially as described. 85
7. A furnace having a grate, a fuel-opening and a smoke-outlet, in combination with an arch or partition dividing the furnace into fire and combustion chambers and containing 90 an opening or throat, forming communication between said chambers, and means for heating air and from numerous points, adjacent to said throat, directing the same forcibly into said fire-chamber, said means being such that a barrier of hot air is formed and maintained in the fire-chamber, tending to repress the flow of gases through said throat and compelling the enrichment of the combustibles prior to their entrance to the 95 combustion-chamber, substantially as described. 100
8. A furnace-chamber, having a grate, a fuel-opening and an outlet, in combination with arches of refractory material, extending 105 transversely of said furnace, there being a throat or opening between said arches and said arches being provided with air passages and deflectors adapted to cause the streams of air to impinge, thus forcibly maintaining a 110 complete hot-air barrier across the furnace beneath said throat, when the furnace is in operation, substantially as described. 115
9. A furnace-chamber, having a grate, a fuel-opening and an outlet, in combination 115 with arches extending transversely of said chamber and having a throat between them, such arches having longitudinal air-channels and transversely-disposed downwardly-inclined air-deflectors adjacent to said throat, 120 adapted to so direct air-currents that the same will converge below the arch and together form a continuous air barrier across and beneath said throat, substantially as and for the purpose specified. 125
10. A furnace-chamber, having a grate, a fuel-opening and an outlet, in combination with front and rear arches arranged in said chamber, separated by a throat, composed of refractory bricks, and containing air-heating 130

channels and also openings for directing converging currents of air into the space beneath said arches, and means for supplying air to the outer ends of the arch-channels, substantially as described.

11. A furnace-chamber, having a grate, a fuel-opening and an outlet, wherein a partial vacuum is maintained by draft through said outlet, and the walls of which chamber are provided with air-admission openings, in combination with transverse arches arranged in said chamber, separated by a throat and having channels communicating with said openings, and said arches being provided at their inner ends only with rearwardly-inclined deflecting-surfaces adapted to direct the currents of air against the outflowing gases and maintain an air barrier upon the inner side of said arches, across said throat.
12. A furnace-chamber, having a grate, a fuel-entrance and an outlet, in combination with supports upon the walls of said chamber, arches separated by a throat and composed of curved bricks arched against one another and sustained by said supports and walls, said bricks containing air-heating conduits or channels communicating with the external atmosphere, and the inner end bricks of both arches having inclined deflecting surfaces or walls, adapted to cause the streams of air to converge beneath the arches, substantially as and for the purpose specified.
13. A furnace-chamber, having a grate, a fuel-opening and an outlet, in combination with refractory arches extending from the vertical walls of said furnace toward the middle of the fire-chamber and providing a restricted throat, and means at the inner ends of said arches for directing currents of heated air toward the fire and causing the same to converge beneath said throat; whereby an air barrier is maintained across said throat, substantially as and for the purpose specified.
14. A furnace-chamber, having a grate, a fuel-entrance and an outlet, in combination

with arches of refractory material, extending from the vertical walls of said chamber toward the middle thereof and providing a restricted throat, deflectors upon the under sides of said arches, said deflectors extending from wall to wall of the furnace and being inclined downwardly and toward said throat, and means for directing rapidly-moving currents of air against said deflectors to maintain the herein-described air barrier beneath said throat, within the fire-chamber, substantially as described.

15. A furnace-chamber, having a grate, a fuel-entrance and an outlet, in combination with arches of refractory material extending from the front and rear walls of said chamber and providing a restricted throat in a plane substantially parallel with said grate, said arches being provided with air-entrance channels and having downwardly-inclined deflecting-surfaces, for forcibly maintaining a barrier of air beneath said throat, substantially as and for the purpose specified.

16. A locomotive-boiler furnace, in combination with a hollow inclined air-feeding arch extending from the lower portion of the flue-sheet of said furnace, said arch being curved in cross-section and having the middle portion of its lower end relatively depressed or straightened to avoid closing the lower flues in said flue-sheet, substantially as described.

17. The cross-sectional curved lower bricks, 23", presenting a curved surface at one edge and a straight surface at the other edge and provided with openings or channels, substantially as described.

In testimony whereof we have hereunto set our hands, this 3d day of September, A. D. 1904, in the presence of two witnesses.

EVAN H. WADE.
JOHN L. NICHOLSON.
